(57) **CLAIM**

The ornamental design for an air sample collector for laboratory use, as shown and described.

DESCRIPTION

The patent or application file contains at least one drawing executed in color. Copies of this patent or patent application publication with color drawing(s) will be provided by the Office upon request and payment of the necessary fee.

1. Air sample collector for laboratory use
2. Air sample collector for laboratory use
- 1.1: front
- 1.2: rear
- 1.3: left side
- 1.4: top
- 1.6: front perspective
- 1.7: rear perspective
- 2.1: front perspective
- 2.2: rear perspective.

The broken lines depict portions of the air sample collector for laboratory use that form no part of the claimed design.
